UNITED STATES PATENT OFFICE.

JOHN T. SIMPSON, OF CHICAGO, ILLINOIS, ASSIGNOR TO ECONOMY SALES COMPANY, OF CHICAGO, ILLINOIS, A CORPORATION OF ILLINOIS.

FURNACE-GRAVE.

1,391,014.

Specification of Letters Patent. Patented Sept. 20, 1921.

Original application filed September 23, 1916, Serial No. 121,709. Divided and this application filed August 19, 1918. Serial No. 250,467.

To all whom it may concern:

Be it known that I, JOHN T. SIMPSON, a citizen of the United States of America, and resident of Chicago, Illinois, have invented 5 a certain new and useful Improvement in Furnace-Grates, of which the following is a specification.

This is a division of my application No. 121,709, filed September 23, 1916, (now Patent No. 1,313,127). In said patent I have claimed the construction and arrangement of the vaporizer. In this divisional application I have claimed the construction and arrangement of the furnace grate. Therefore, in said prior application no claim is made for the particular form of grate construction shown and described, and in this divisional application no claim is made for the vaporizer.

20 My invention relates to furnace grates in general, but more particularly to those of that kind in which a central section, which is movable, is surrounded by other grate sections.

25 Generally stated, one object of my invention is to provide an improved grate construction of this general character in which the central section is oscillatory, and in which the central section is surrounded by 30 stationary grate sections, movable grate sections being arranged outside of the stationary sections, thereby to effect the combustion of the fuel in a manner which will be efficient and effective for any desired purpose. Another object is to provide a grate adapted for making water gas.

It is also an object to provide certain details and features of construction and combinations tending to increase the general efficiency and desirability of a furnace grate of this particular construction.

To the foregoing and other useful ends, my invention consists in matters hereinafter set forth and claimed.

45 In the accompanying drawings—

Figure 1 is a plan of a furnace grate embodying the principles of my invention.

Fig. 2 is a side elevation of the structure shown in Fig. 1.

50 Fig. 3 is a transverse section on line 3—3 in Fig. 1.

Fig. 4 is a transverse section on line 4—4 in Fig. 1.

Fig. 5 is a detail view illustrating the construction of the water-receptacle which extends around the entire grate structure. 55

Fig. 6 is a plan of the center frame which supports the oscillatory center section of the grate.

Fig. 7 is an enlarged detail plan view of 60 one corner portion of the grate structure.

Fig. 8 is a sectional view illustrating a form of apparatus for automatically supplying water to the water-receptacle.

As thus illustrated, my invention comprises the horizontal and longitudinally extending frame-bars or stationary grate-members A, B, C and D which rest on the walls E and F at their opposite ends, said walls being of any suitable character. 65 Transverse end-bars G and H connect the bars A, B, C and D together, these end-bars being provided with slots g and h, respectively, and bolts I and J extending through these slots and through the longitudinal 70 slots a, b, c and d in the longitudinal bars, in the manner shown more clearly in Fig. 7, whereby all of these bars can expand and contract easily without distorting the structure. The stationary frame K, shown more 75 clearly in Fig. 6, is bolted at k to the under sides of the longitudinal bars B and C, and is provided with a vertical center-post or pivot L which forms the axis of the ball-bearing l, the latter being of any suitable 80 character. The center grate-section M is shaped like an obtuse cone, being composed of a middle portion m having outer removable sections N secured by bolts n thereto. The portion m is supported by the ball-bearing l, so that no weight is supported by the upper end of the post or pivot L, the latter serving merely to center the grate section M 85 in the desired manner. The hand-lever O is connected by a link o with an arm 1 which depends from one side of the grate section M, said hand-lever being suitably pivoted to operate about the horizontal axis 2 at the front of the furnace. With this shaker arrangement, and by vibrating the hand-lever 90 O, the center grate section M is alternately oscillated in opposite directions about a vertical axis, thereby to shake the fuel thereon.

The stationary bars B and C are provided with openings or slots 3, so that these bars 100 or stationary members serve as stationary

grate sections, being disposed at opposite sides of the central oscillatory section N, and in the plane of the lower edges of the latter. The stationary grate sections P and Q are supported transversely of the grate and connected to the bars B and C at p and q, respectively, and are provided with curved and toothed inner edges which are disposed at the base of the conical oscillatory center section M, whereby the latter is entirely surrounded by stationary grate sections, and whereby there are no rocking grate sections or any movable grate sections at the base of the oscillatory center section. It will be seen, however, that the transverse rocking grate bars R and S have their end-bearings or trunnions r and s, which may be of any suitable shape, located to turn and rock in recesses 4 on the longitudinal bars B and C. These bars have their teeth arranged to extend between the teeth 5 on the cross-bars G and H, and also between the teeth 6 of the stationary grate sections P and Q, whereby transverse rocking grate sections are provided in front and rear of the stationary grate sections which are disposed immediately in front and in rear of the oscillatory center grate section. It will also be seen that the shorter transverse rocking grate bars T and U have their end-bearings or trunnions t and u arranged to turn or rock in the recesses 7 and 8 on the outside sills or longitudinal bars A and D, and in the recesses 9 and 10 formed in the bars B and C, in a manner that will be readily understood. Thus, the space between the longitudinal members A and B is occupied by the transversely arranged rocking grate bars T, while the similar space between the longitudinal members C and D is occupied by the rocking grate bars U, whereby rocking grate sections are provided at opposite sides of the stationary grate sections. The pivoted hand-lever V is connected by a link v with the depending arms 11 on the grate bars U, and also with the depending arm 12 on one end of the rocking grate bar S, whereby the operation of this hand-lever causes the grate bars U and S to rock about horizontal axes in the bearings provided for this purpose, as previously described. Another pivoted hand-lever W is connected by a link w with the depending arms 13 on the rocking grate bars T, and with a similar arm on one end of the rocking grate bar R, whereby the operation of this lever serves to rock all of said grate bars.

Thus, the oscillatory center section M is controlled by the hand-lever O, in the manner explained, while the rocking grate bars U and S are controlled by the hand-lever V, and the grate bars T and R are controlled by the hand-lever W, in a manner that will be readily understood. The stationary grate bars or grate sections are disposed at the

base of the oscillatory center section, and completely surround the latter, (the sections P and Q may be united or made integral, as shown, if desired), and the rocking grate bars or grate sections are disposed outside 70 of said stationary grate bars or grate sections, in the horizontal plane thereof, so that a portion of the burning fuel is supported on stationary grate sections occupying an area between the oscillatory center 75 section and the outer rocking sections. Furthermore, the center section M does not rotate, but is merely oscillatory about a vertical axis.

A rectangular water-receptacle or vaporizer X extends around the entire grate structure, in the manner shown in Figs. 3 and 4, this water-receptacle consisting of four straight sections connected together at their ends, and at the corners of the grate structure, by bolts x, and end portions of the water-receptacle sections being slotted to permit them to slide on said bolts, thereby providing for expansion and contraction. The outer rectangular frame of the grate 90 is formed by the longitudinal members A and D and the cross-bars G and H, and each member and each cross-bar has a section of said water-receptacle allotted thereto. It will also be seen that the said water-receptacle sections are connected at their ends by suitable tubes Y, whereby the water may circulate from one section to the other. A water-tank Z is connected by a pipe z with the said water-receptacle X, as shown more 95 clearly in Fig. 8, and is provided with an inlet-valve 14 which is automatically controlled by a float 15 within the tank, so that the latter is kept full of water. The flat box-like members which thus form the vaporizer have their outer flat walls provided with vents 16 for the steam, these outlets being disposed along the upper edge of each member. The frame of the grate structure overhangs the tops of these box-like members, and extends downwardly inside thereof, close to the inner walls of the vaporizer, as shown in the drawings. As fast as the water evaporates, the water-receptacle has a fresh supply of water from the tank Z, in 110 a manner that will be readily understood. In this way, the rim or outer frame-portion of the grate structure is provided with a steam or vapor generating receptacle. The exact manner in which the vaporizer is 115 mounted on the rim or outer frame of the grate is unimportant, and may be of any mounted on the rim or outer frame of the grate is unimportant, and may be of any suitable character, such as bolts, screws or hooks or other common or ordinary means, for the essential feature is, as stated, that 125 the rim or outer frame portion of the grate structure is provided with a vaporizer, and that the grate is supported by means entirely distinct from and independent of said vaporizer, and with this arrangement the va- 130

porizer does not support the grate, and the steam generated will escape through the vents 16 into the ash-pit below the grate, and will then be drawn up through the grate 5 by the draft of the furnace. The walls 17 of the furnace form the combustion-chamber 18 above the grate and the ash-pit 19 below in which the vaporizer is inclosed. It will be understood, of course, that the tube-connections Y are of such character that they will yield slightly, so that the expansion and contraction of the sections X will be taken care of in the desired manner. Also, the vaporizer thus shown and described is adapted 10 for removal upwardly with the grate structure, from the supporting means F and E, being associated therewith, but could be made detachable without disturbing the grate, as the vaporizer does not support the 15 grate in any way or to any extent. The steam or water vapor drawn up through the grate will pass through the burning fuel and be converted into water gas in the well-known manner. For this purpose, coke is 20 ordinarily employed as the fuel and in this way the grate can be used in a furnace for any ordinary purpose, and at the same time water gas will be produced. As the bars E and F support the removable grate structure, it is obvious that the vaporizer does 25 not sustain any part of the weight of the grate structure, and that the vaporizer can be omitted from the structure without depriving the grate of its support and, obviously, the vaporizer comprising the sections 30 X can be mounted on the removable grate structure or can be supported on the stationary end bars E and F of the grate structure in such a way that the vaporizer itself 35 is readily removable from the furnace. As explained, though, this feature of the invention is not limited to any particular means, ordinary or otherwise, for supporting the vaporizer, either on 40 the grate or otherwise, the invention contemplating broadly, as claimed in said prior application, a structure of this kind in which the important consideration 45 is that the vaporizer is distinct from and independent of the grate structure, in the sense that the grate proper, in its entirety, is supported by means independent of and structurally distinct from the vaporizer, so that 50 the vaporizer does not support any portion 55 of the weight of the grate and may, therefore, as shown and described, be entirely constructed and arranged merely with respect to its function as a vaporizer, and for 60 that purpose alone. Any form of vaporizer, of course, can be employed, but the vaporizer shown and described is especially adapted for this purpose, and the grate shown and described is especially designed and adapted for use in 65 conjunction with a vaporizer, and hence the

vaporizer is shown (but not claimed, being claimed in said prior application), to illustrate the adaptability of the grate for this purpose.

With the construction shown and described, it will be seen that the upper surfaces of the outer longitudinal side members A and D form part of the top surface of the grate, being flush with the longitudinal middle structure of the grate, so that 75 the entire grate structure is practically flat on its upper surface around the cone-shaped oscillatory middle section M, and the entire grate has a rigid rim or outer edge at all sides thereof. In this way, the grate 80 structure is complete in itself, all of the movable grate-bars or sections being supported by means forming part of the grate structure, so that the entire grate structure could be lifted upwardly as a unit. With 85 the rocking grate-bars arranged transversely of the grate, the shaking movement is easily and conveniently imparted thereto by means disposed at the front of the furnace, and through connections having movement longitudinally of the grate. Also, by oscillating the central or cone-shaped middle section M of the grate, a shaking motion is 90 communicated thereto, to shake the ashes through the openings thereof, and to shake 95 the fuel around and throw it outwardly upon the surrounding surface of the grate, when desired, and in this way the grate is prevented from clogging, and the proper combustion of the fuel is maintained in the 100 desired manner.

What I claim as my invention is:—

1. In a furnace grate construction, the combination of parallel and longitudinally disposed outer members forming the side 105 edges of the grate, each member being provided with notches along its inner edge, a longitudinally disposed central structure having stationary grate sections and formed along its outer edges with notches opposite 110 those of said outer members, transverse rocking grate-bars supported in said notches, transverse stationary grate bars forming the front and rear edges of the grate and connecting together the outer longitudinal 115 members and said middle structure, so that the top of the grate has a rigid rim at all sides thereof, movable grate sections incorporated in said middle structure, said longitudinal members and middle structure having projecting front and rear end portions, and supporting means upon which said end portions rest in a horizontally disposed plane.

2. A structure as specified in claim 1, said 125 grate having transverse and longitudinal slots at the corners thereof, with bolts extending through said slots, substantially as shown and described.

3. A structure as specified in claim 1, said 130

- movable grate sections of the middle structure comprising an oscillatory cone-shaped section forming the center of the grate, and transverse rocking grate-bars in front and 5 rear of said cone-shaped section.
4. A structure as specified in claim 1, said outer longitudinal members forming part of the top surface of the grate and being flush with the middle structure.
- 10 5. In a furnace grate, the combination of parallel rows of rocking bars, stationary means forming part of the grate surface and having four portions extending in opposite directions therefrom, provided with bearings for said rocking bars, a single rocking bar between two of said portions, a single rocking bar between the other two portions, stationary bars forming bearings for the outer ends of said rows of rocking bars, 15 and stationary bars extending transversely of said rows, said stationary bars being all connected to form a rectangular outer frame for the grate.
- 20 6. A structure as specified in claim 5, said
- single rocking bars being axially alined with the bars at the ends of said rows.
7. In furnace grate construction, an oscillatory center section, a shaker having means for oscillating said section about a vertical axis, stationary grate sections arranged at 30 the base of the center section and providing a stationary fuel-support extending around the oscillatory center section, rocking grate sections associated with the stationary grate sections, said rocking grate 35 sections comprising a row of transverse grate-bars at each side of the stationary grate sections, and including also a transverse rocking grate-bar disposed in front and in rear of said stationary grate-sections 40 and in alinement with the end members of said rows, in combination with means forming a rectangular frame for the outer edges of the grate and having bearings for certain of said rocking sections, together with 45 means projecting from the grate for the support thereof in a furnace.

JOHN T. SIMPSON.
